HAT SUPPORT

Elio R. Caruso, Hartford, Conn.

Application July 29, 1933, Serial No. 682,784

4 Claims. (Cl. 206—8)

My invention relates to a class of devices employed for supporting a hat, particularly in a bag to prevent the brim from being bent, and an object of my invention, among others, is the production of a support of this type that shall be simple in construction and that shall effectually perform the functions required of it.

One form of a device embodying my invention and in the construction and use of which the objects herein set out, as well as others, may be attained is illustrated in the accompanying drawing, in which—

Figure 1 is a side view of a bag partially torn away to illustrate my improved hat support therein.

Figure 2 is a view in section through said bag showing the hat support therein from a point at right angles to the point of view of Fig. 1.

Figure 3 is an isometric view of my improved hat support.

Figure 4 is a face view of the same.

It is common practice at the present time in the sale of hats to place the hat in a paper bag with the brim resting upon the bottom of the bag, and this results in the brim being bent out of shape thereby destroying the neat appearance of the hat when removed from the bag. With my improved support, illustrated and described herein, this objectionable feature is removed, the hat being supported by the crown with the edge of the brim clear from the bottom of the bag, such support being illustrated in the accompanying drawing in which the numeral 5 denotes the base of my improved support and 6 a hat rest formed integral with the base. This structure is preferably composed of pasteboard or similar material which may be cut to shape by means of dies and which may be shipped flat thereby economizing space in transportation or it may be folded if desired.

A brace 7 is cut out from an opening 8 in the base, said brace having its end formed as a tuck 9 to be engaged in a loop 10 made by forming slits 11 a short distance apart in the rest 6.

The opposite edges of the base 5 are obliquely formed, said edges approaching each other in the direction of the rest 6 so that the ends 12 of the rest are separated from the base for a considerable portion of their length. This enables said rest to be curved to conform somewhat to

the curved shape of the crown 13 of the hat which is of a soft character, as of felt, and as shown in Fig. 1.

With the support bent to the form shown in Figures 1, 2 and 3 it is inserted in a bag 14 with the bottom edge of the base 5 resting upon the bottom of the bag. The hat then being placed in the bag the crown 13 will lie upon the rest 6 and the brim 15 will be supported with its edge at some distance from the bottom of the bag, thereby preserving the brim in its natural shape and preventing its being wrinkled or creased.

I claim:

1. A hat support composed of pasteboard or similar material and including a base member, a rest member bendable at an angle to said base, and a brace cut out from the material comprising one of said members and projecting from the edge of the opening thus formed in said member diagonally across said angle into engagement with the other of said members.

2. A hat support composed of pasteboard or similar material and including a base member having a broad bottom edge with ends tapering toward each other, a rest member bendable at an angle to said base and projecting beyond the end edges of said base forming flaps bendable to conform to the crown of a hat, and means for retaining the base and rest at an angle one to the other.

3. A hat support composed of pasteboard or similar material and including a base member, a rest member bendable at an angle to said base, and a brace formed of a piece cut from said base and bent out of an opening therein to engage said rest member to hold it in its angular position with respect to the base.

4. A hat support composed of pasteboard or similar material and including a rest member, a base member bendable at an angle to said rest member and having end edges inclined outwardly away from said rest member thereby providing flaps at the ends of said rest member bendable to conform to the shape of the crown of a hat, a brace cut from one of said members and bendable out of an opening therein, and a loop formed by parallel slits in the other member bent for engagement by the end of said brace.
